CLOTHES-DRYING RACK

Simon Wigod, New York, N. Y., assignor to Louis Schissel, Flushing, N. Y.

Application July 17, 1943, Serial No. 495,145

8 Claims. (Cl. 211—86)

This invention relates to clothes drying racks. It is particularly directed to a collapsible clothes drying rack which may be readily mounted on a door in position for use without necessity for any attaching devices.

An object of this invention is to provide a drier of the character described having extensions adapted to engage beneath the door knobs, and a portion engaging the door latch so that the rack is supported in horizontal position for use.

Another object of this invention is to provide a device which may be easily set up for use or removed, and which is collapsible into a compact form for shipping or storing.

Still another object of this invention is to provide a rugged, and compact and durable device of the character described which shall be relatively inexpensive to manufacture, light in weight, easy to handle and manipulate, and which shall yet be practical and efficient to a high degree in use.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawing, in which is shown various possible illustrative embodiments of this invention,

Fig. 1 is a side elevational view of a drier embodying the invention, on a door;

Fig. 2 is a cross-sectional view taken on line 2—2 of Fig. 1;

Fig. 3 is a top plan view of the drier in collapsed condition; and

Fig. 4 is an enlarged cross-sectional view taken on line 4—4 of Fig. 2.

Referring now in detail to the drawing, reference numeral 10 designates a clothes drying rack embodying the invention. The rack 10 comprises a pair of parallel, flat end members 11 and 12 which may be made of wood or any other suitable material. The members 11, 12 are in a common plane and in alignment or co-extensive with one another. Interconnecting said members 11, 12 are a pair of parallel rods 13, which may be made of round stock. Members 13 may likewise be made of wood or any other suitable material. They are pivotally connected to members 11, 12 by vertical rivet 16 passing through suitable registering openings 17 and 18

in members 11 and 12 and rods 13, respectively. Between rods 13 and end members 11, 12 and on the rivets, are washers 16a.

The rivets 16 have flat heads 20 at their upper ends and may be provided with flat washers 21 at their lower ends retained on the rivet by the upset lower ends 22 of the rivets.

It will now be understood that rods 13 and portions of members 11, 12 form a parallelogram so that as the rack is collapsed members 11, 12 remain parallel to each other, while rods 13 remain parallel to each other.

It will further be understood that members 11, 12 have wing portions extending beyond the rods 13 on opposite sides. Interconnecting each pair of wing portions are cords 25, 26 which may be passed through vertical openings 25a, in members 11, 12 to form parallel clothes engaging portions. The ends of the cords 25, 26 may be knotted to retain said cords in relatively taut condition.

The rods 13 extend beyond member 11 to form extensions 13a for the purpose hereinafter appearing.

25 Fixed adjacent the outer ends of extensions 13a are rubber knobs 30 projecting upwardly from said rods. The knobs 30 may be fixed to the extensions 13a in any suitable manner. The upper portions of the extensions 13a adjacent 30 the knobs 30 may be formed with grooves or cuts 31 or otherwise roughened for the purpose hereinafter appearing.

The way of using the clothes rack is illustrated in the drawing. The extensions 13a are 35 passed beneath the door knobs 40 of a door 41. The latch 42 of the door is passed beneath member 11.

It will be noted that the extensions 13a straddle the door. The rack 10 is thus supported 40 due to engagement of the extensions 13a with the knobs 40 and engagement of the latch 42 with the underside of member 11. The roughened portions or cuts or grooves 31 engaging the shanks of the door knobs serve to frictionally retain the rack against accidentally sliding off. Knobs 30 serve as an added precaution to engage the door knob and keep the rack on the door.

It will now be understood that the rack may 50 be easily set up by merely opening it up, passing the extensions 13a beneath the door knobs, and resting member 11 on the door latch. It will then be in horizontal position, ready for use. The rack may just as easily be removed by taking it off the door.

It can then be collapsed to compact condition and stored in the closet.

If desired member 11 of the rack may be formed as illustrated in Figs. 2 and 4 with a groove 50 adjacent one of the rivets 16. The rivet 16 may move through groove 50 to permit opening up of the angle between the rods 13 so as to accommodate doors of various widths.

Inserted into one end of the groove is a longitudinal pin or peg 53. On the peg 53 and within the groove is a coil compression spring 54 which is interposed between one end of the groove and the rivet 16. The spring 54 keeps the rod extensions 13a pressed against the door, thus permitting application of the rack to doors of various widths.

The spring pressure furthermore helps retain the rack on the door against accidental dislodgment thereof.

It will thus be seen that there is provided a device in which the several objects of this invention are achieved, and which is well adapted to meet the conditions of practical use.

As various possible embodiments might be made of the above invention, and as various changes might be made in the embodiments above set forth, it is to be understood that all matter herein set forth or shown in the accompanying drawing is to be interpreted as illustrative and not in a limiting sense.

Having thus described my invention, I claim as new and desire to secure by Letters Patent:

1. A rack, comprising a pair of parallel, co-extensive, aligned members, a pair of parallel rods pivoted to said members and being disposed transversely thereof and forming a parallelogram therewith, said rods having extensions extending beyond one of said parallel members, and adapted to straddle a door and engage beneath knobs on the opposite sides of the door, said one of said parallel members being adapted to engage the top of the latch of the door, said parallel members having wing portions extending beyond said rods, and cords interconnecting said wings on which to suspend clothes.

2. A rack, comprising a pair of parallel, co-extensive, aligned members, a pair of parallel rods pivoted to said members and being disposed transversely thereof and forming a parallelogram therewith, said rods having extensions extending beyond one of said parallel members, and adapted to straddle a door and engage beneath knobs on the opposite sides of the door, said one of said parallel members being adapted to engage the top of the latch of the door, said parallel members having wing portions extending beyond said rods, and cords interconnecting said wings on which to suspend clothes, said extensions being roughened at their upper sides.

3. A rack, comprising a pair of parallel, co-extensive, aligned members, a pair of parallel rods pivoted to said members and being disposed transversely thereof and forming a parallelogram therewith, said rods having extensions extending beyond one of said parallel members, and adapted to straddle a door and engage beneath knobs on

the opposite sides of the door, said one of said parallel members being adapted to engage the top of the latch of the door, said parallel members having wing portions extending beyond said rods, cords interconnecting said wings on which to suspend clothes, and knobs adjacent the outer ends of said extensions and on the upper side thereof.

4. A clothes drying rack, comprising a pair of parallel members, a rod pivoted to said pair of parallel members, one of said pair of parallel members being formed with a longitudinal groove, a second rod pivoted to the other of said parallel members, a pin on said second rod passing through said groove, and a spring interposed between said pivot pin and one end of the groove to permit spreading of said rods, said rods having extensions adapted to straddle a door and engage beneath the knob on the door, one of said parallel members being adapted to engage the top of the latch of the door.

5. A clothes drying rack, comprising a pair of parallel members, a rod pivoted to said pair of parallel members, one of said pair of parallel members being formed with a longitudinal groove, a second rod pivoted to the other of said parallel members, a pin on said second rod passing through said groove, and a spring interposed between said pivot pin and one end of the groove to permit spreading of said rods, said rods having extensions adapted to straddle a door and engaging beneath knobs on the door, one of said parallel members being adapted to engage the top of the latch of the door.

6. A clothes drying rack comprising a pair of parallel co-extensive members, a pair of parallel rods pivoted to said members, said rods having extensions adapted to straddle a door and engage beneath knobs on opposite sides of the door, one of said parallel members being adapted to engage the top of the latch of said door, and means interconnecting said parallel members on which to suspend clothes.

7. A clothes drying rack comprising a pair of parallel co-extensive members, a pair of parallel rods pivoted to said members, said rods having extensions adapted to straddle a door and engage beneath knobs on opposite sides of the door, one of said parallel members being adapted to engage the top of the latch of said door, and means interconnecting said parallel members on which to suspend clothes, said extensions having upward projections adapted to engage the door knobs.

8. A clothes drying rack comprising a pair of parallel co-extensive members, a pair of parallel rods pivoted to said members, said rods having extensions adapted to straddle a door and engage beneath knobs on opposite sides of the door, one of said parallel members being adapted to engage the top of the latch of said door, and means interconnecting said parallel members on which to suspend clothes, said extensions having upward projections adapted to engage the door knobs, said extensions having transverse grooves on their upper surfaces.

SIMON WIGOD.
